UNITED STATES PATENT OFFICE.

EDWARD F. POLAND, OF BOSTON, MASSACHUSETTS.

HYDRO-EXTRACTOR.

1,094,590.

Specification of Letters Patent. Patented Apr. 28, 1914.

Application filed June 12, 1913. Serial No. 773,211.

To all whom it may concern:

Be it known that I, EDWARD F. POLAND, a citizen of the United States, residing at Boston, in the county of Suffolk and State of 5 Massachusetts, have invented an Improvement in Hydro-Extractors, of which the following is a specification.

This invention relates to hydro-extractors having a belt-drive, and has for its object 10 to provide the receptacle containing the basket with a closing-lid, and with means connected with said lid and adapted to engage or interlock with the belt-pulley when the belt-pulley is at rest but not to engage 15 therewith when the belt-pulley is revolving, said means controlling the opening of the lid, whereby the lid can be opened only when the machine is at rest, and said means being also so constructed and arranged as 20 to require the closing of the lid before the machine is started.

The invention involves essentially a trig 25 adapted to be moved into any of the openings between the spokes of the belt-pulley, or it may be an opening especially provided in the belt-pulley, and when thus engaging said pulley the machine cannot be started until the trig is moved out of engagement therewith; and said trig is yieldingly sup- 30 ported so that in case it should be moved into engagement with the pulley while the pulley is revolving the spokes of the pulley will strike the end of the trig and repeatedly move it backward, and produce a loud noise, 35 thereby to notify the operator that the machine has not yet come to rest. Said trig is connected by suitable mechanism with the closing-lid so as to be moved in one direction upon opening said lid and in the 40 other direction upon closing it.

My invention is applicable to any of the well-known forms of hydro-extractors having belt-pulleys at the base of the machine or at the top, or elsewhere disposed, the 45 mechanism connecting the trig with the closing-lid being changed to accommodate the position of the belt-pulley.

Figure 1 is a front elevation of a hydro-extractor embodying this invention having 50 a closing-lid and means for controlling its movement. Fig. 2 is a right-hand side elevation of the hydro-extractor shown in Fig. 1. Fig. 3 is a fragmentary view of the closing-lid and connecting means. Fig. 4 55 is a horizontal section on the dotted line $\alpha-\alpha$ Fig. 1. Figs. 5 and 6 are views of

modifications of the invention applied to other forms of hydro-extractors than that shown in Fig. 1.

Referring to Figs. 1 to 4 wherein one type of hydro-extractor with belt-drive is shown, 60 10 represents the receptacle containing the basket 12; 13 and 14 belt-pulleys over which a belt passes, which also passes around a belt-pulley 15 on the upright shaft of the basket. 18 is a closing-lid for the receptacle 10, and, as here shown, said lid is connected with the receptacle by a hinge 19, of any suitable construction, 20 representing the pintle or pivot-pin of the hinge. Said 65 closing-lid has a handle 22 by which it may be moved up and down as occasion may require, thereby to open and close the opening at the top of the receptacle. As represented in said figures, a link 25 is loosely connected at one end to an ear 26 at the top of the hinge, or it may be elsewhere loosely connected with the closing-lid, the other end of said link being loosely connected with a short arm 28 arranged at the upper end of an upright rod 29, said arm being arranged 70 at right angles to said rod or thereabout, whereby upon longitudinal movement of the link said arm will be swung in a substantially horizontal plane and said rod will be 75 correspondingly oscillated. Said link is disposed between a pair of ears 30 arranged at the top of the receptacle by which it is held against lateral movement; and said 80 oscillating rod has suitable bearings on the side of the receptacle. To the lower end-portion of said rod a short arm 32 is secured, which is extended from the rod at an angle and is swung back and forth in a substantially horizontal plane by the oscillating rod. 85 Said short arm 32 occupies a position between a pair of pins 35, projecting upward from a bar 36, which is slidably supported in end-bearings provided for it. Said bar is arranged adjacent one of the belt-pulleys, 90 as 13 for instance, and one of its end-portions is movable into and out of engagement with said pulley, as for instance, said end-portion is movable into and out of any of the openings between the spokes of said 95 pulley or any opening which may be purposely provided for it in the pulley. Said sliding-bar serves as a trig for the belt-pulley, as when in engagement therewith said belt-pulley is held at rest. By the connecting-means here shown between the closing-lid and the trig it will be seen that as 100 105 110

the lid is raised the link 25 will be moved longitudinally and the rod 29 will be oscillated and the trig will be moved into engagement with the belt-pulley, and as the 5 closing-lid is lowered said trig will be moved in the opposite direction for disengagement from the belt-pulley. When the trig is in engagement with the belt-pulley the closing-lid is held open and the machine cannot 10 be started for the reason that the trig holds the belt-pulley at rest. When it is desired to start the machine the closing-lid must be closed, and thereupon the trig is moved out of engagement with the belt-pulley and the 15 belt-pulley is then free to rotate. While the belt-pulley is rotating should an attempt be made to open the closing-lid it will be seen that the trig will be moved into engagement with said pulley and the spokes 20 thereof will repeatedly engage the end-portion of the trig and will repeatedly move said trig backward, making a loud noise, and thus calling the attention of the operator to the fact that the belt-pulley is 25 rotating and the machine is still running.

Referring to Fig. 5, wherein another type of hydro-extract or with belt-drive is shown, the belt-pulley 50 is arranged at the top of the machine and the closing-lid 18 is connected with the receptacle in the same manner as previously described, and a link 55 is loosely connected to an ear on the hinge of the closing-lid, which loosely engages an upright pin 56, rising from a sliding-bar 57 30 or trig which is arranged in suitable bearings at the top of the receptacle adjacent the belt-pulley 50, said bar being movable into and out of engagement with said belt-pulley in substantially the same manner as heretofore 35 described, by sliding it in opposite bearings.

Referring to Fig. 6 another form of hydro-extract or with belt-drive is shown having a belt-pulley 60 arranged at the top of the machine, and in this instance a slidably supported trig 65 is employed which is engaged by one arm 66 of a bell-crank lever, the other arm 67 of said lever being loosely connected by a link 68 with an ear on the closing-lid 18. These several forms of hydro-ex- 40 45

tractors are shown as illustrating some of 50 those to which my invention is applicable, and I desire it to be understood that other forms may be employed in lieu of those here shown; and furthermore, that other forms of connecting-means between the trig and 55 closing-lid may be employed, and also trigs of other forms, without departing from the spirit and scope of my invention.

I claim:—

1. In a hydro-extractor having a belt- 60 drive, a pivotally supported closing-lid for the receptacle containing the basket, a trig slidably supported for engagement with and disengagement from the belt-pulley, and means connecting said trig with the closing-lid whereby the trig is slid upon movement of the lid, substantially as described.

2. In a hydro-extractor having a belt-drive, pivotally supported closing-lid for the receptacle containing the basket, a bar slidably 70 supported at the side of the belt-pulley and movable into and out of an opening in said pulley, and means connecting said bar with the closing-lid whereby it is moved longitudinally upon movement of said lid, sub- 75 stantially as described.

3. In a hydro-extractor having a belt-drive, a closing-lid for the receptacle containing the basket, pivotally supported thereon and arranged for movement up and down, a link 80 loosely connected with said lid and movable longitudinally upon movement thereof, an upright rod adapted for oscillation, having a short arm at its upper end which is loosely connected with said link and having a short 85 arm at its lower end, and a slidably supported trig arranged adjacent the belt-pulley and adapted to engage and disengage said pulley, said trig having means for operatively connecting it with said last-named short 90 arm, substantially as described.

In testimony whereof, I have signed my name to this specification, in the presence of two subscribing witnesses.

EDWARD F. POLAND.
